UNITED STATES PATENT OFFICE.

PETER KRUMSCHEID, OF BOSTON, MASSACHUSETTS.

BROOM OR BRUSH.

1,378,037.

Specification of Letters Patent. Patented May 17, 1921.

Application filed September 6, 1919. Serial No. 322,097.

To all whom it may concern:

Be it known that I, PETER KRUMSCHEID, citizen of the United States, residing at Boston, in the county of Suffolk and State of Massachusetts, have invented new and useful Improvements in Brooms or Brushes, of which the following is a specification.

The present invention relates to brooms or brushes, and, in fact, to any article of that nature which comprises tufts of brush material and a holder for such tufts. It is particularly suited for brooms of such stiff and coarse character as are used for street sweeping, and of which the brush material consists of ratan or other reeds, either split or whole, and I have, for the purpose of illustration in the drawings furnished herewith, shown a broom of this specific character. It is to be understood, however, that the principles in which the invention consists are applicable to brooms or brushes of a great variety of sizes and containing brush materials of various sorts, useful for different purposes.

One object which I have had particularly in view has been to produce a construction of the sort indicated, which can be made by the blind, and one which also is strong and rigid, and is adapted to secure the tufts of brush material with exceedingly great firmness.

The principles and means in which the invention consists may be best explained in connection with the following description and appended drawings of one form of broom which I have made embodying these principles.

In these drawings:

Figure 1 is a face view of one species of such broom.

Fig. 2 is a vertical section between two tufts of the broom.

Fig. 3 is a cross section, taken about on line 3—3 of Fig. 1.

Fig. 4 is a plan view of the members which collectively form the sockets or binding means for the tufts of brush material.

Figs. 5 and 6 are respectively a cross section and an elevation of a somewhat modified form of the invention.

Fig. 7 is a plan view of one of the binder members employed in said modified construction.

Like reference characters indicate the same parts in all of the figures.

Referring first to the construction illus-

trated in Figs. 1 to 4, *a, a* represent the tufts of brush material, which are here shown as being composed of split ratan; and *b* represents the handle. The form now being described consists of seven tufts in line, of 60 which the middle tuft is composed of strips or reeds arranged so as to surround the lower end of the handle.

These tufts are mounted and secured in two holders or binders, each consisting of 65 two members, one of which is arranged to grip the tufts near their upper ends, the other to grip the tufts at a lower point. The upper and lower holders are substantially alike, and are shown in the drawings as being exactly alike, as to each of the two forms represented, wherefore a description in detail of one is sufficient for both, and both are designated by the same reference letters. They may, however, be made somewhat dif- 70 ferent from one another in dimensions and proportions, as is later described.

The two members designated *c* and *d* of one of these holders are shown separated in Fig. 4, for greater clearness. They may be 80 made of metallic wire, practically any metal being suitable for this purpose, provided it is strong and flexible enough without being brittle, and is not too expensive. In section, the wire may be round, or flattened to a 85 greater or less extent through its whole length or in any selected parts. The ends of the wires are provided with eyes *e, f*, and between the ends each wire is bent in a somewhat zigzag form to make half-sockets *g*, 90 and relatively narrow loops or tongues *h*. The half-sockets are adapted to receive the tufts *a*, and the intermediate loops to pass between the tufts.

In making up the broom, the tufts are 95 preferably first bunched in any suitable way, including the modes of operation now practised, and, when thus assembled, are laid in the socket bends of one of the holder members. Then the complementary member of the 100 same holder is laid against the opposite sides of the tufts so placed, and pressure is exerted upon one of these members toward the other, enough to bring the eyes at their ends into registry. Conveniently, the members of both holders which form the socket halves at the same side of the broom are laid 105 in a properly formed bed, and the tufts are placed in a horizontal position at the same time in both, the opposite members of the 110

two holders then being preferably applied and pressed down upon the tufts at the same time. When the complementary eyes are so registered, they are secured together by locking pins *j* and *k*, as shown in Fig. 1. Here the same pins are shown as passing through the eyes on the same end of the broom of both holders; but, of course, this detail may be modified, and separate pins or rivets of any suitable sort applied independently to each holder.

The operation thus far described results in the halves of one or both holders being secured together at their ends but not elsewhere, each of the holder members then having narrow loops passing between the tufts and overlying one another, but having no interlocking effect. Then the holders are locked between the adjacent tufts by passing a tool through each pair of overlapping narrow loops or tongues, and giving the two a twist about a line which runs from one end to the other of the connected members. This twisting movement carries the tongue which projects from the member *c* downward between two adjacent sockets *g* of the opposite member *d*, and at the same time bends the underlying loop or tongue of the member *d* upward between the opposite half-sockets of the member *c*. The loops, thus bent, form hooks which interlock; and not only do that, but also draw the opposite halves of the sockets on each side of them toward one another against the broom tufts. By carrying forward the twisting effect more or less far, the socket halves may be drawn more or less tightly about the tufts. It becomes possible thus to apply such a firm grip as to make it practically impossible for the tufts or any part of them to work loose and fall out.

Of course, any means already known for binding the individual pieces in a broom tuft together, or for producing increased friction between their contacting surfaces,—such as glue, cement, a coating of paint, a filling of rosin or whatever,—may be used in making brooms according to my invention, to prevent interior reeds from slipping endwise past the outer reeds gripped by the holders.

All of the tufts are thus individually gripped as tightly as may be needed, in two places.

The upper and lower holders need not be exactly alike in size and dimensions, and I contemplate making them different to this extent, that in the lower holder the loops or sockets may be widened or spaced farther apart than those of the upper holder, while the sockets of the latter may be narrower or spaced closer together than as shown in these drawings. Thereby the tufts are inclined toward one another, with the result that their upper or butt ends are placed

close together and their brush ends are spread apart.

The modification in Figs. 5, 6 and 7 represents a mode of diminishing the width of the brush by combining the three middle tufts into two. That is, whereas, in Figs. 1 and 3, the middle tuft is wrapped about the handle, in Figs. 5 and 6 the two tufts at each side of the middle are brought close up against the sides of the handle, which latter is even recessed at its lower end, as indicated at *b'* and *b²*, to contain them, and no reeds are around the handle. The binders for this form are in principle like those already described, but different in the respect that the middle socket or loop *h'* is made of extra width, being, in fact, sufficiently wide to embrace the two middle tufts and the interposed handle. There is substantially no greater distance between the two tufts which are thus placed against the handle than between any other two, because, as appears from Fig. 5, the handle may be recessed deeply enough, without objectionable loss of strength, to make its thickness between the tufts no greater than the space needed for the locking loops between other tufts.

As I have already intimated, the same invention may be applied to making brushes of various sorts, and in this use of the term "brush" I intend to include brooms as well, and indeed all articles of like nature which comprise a holder and tufts of any sort of brush material, whether such material is bristles, broom-corn, reeds, or what not; and the term "brush" as used in the claims has like significance. Thus, for making brushes of larger or smaller size, wire of larger or smaller gage may be used in the holders, and brush material of the more fragile sorts may be protected from being cut or broken under the pressure of these holder members by a wrapping of comparatively stiff material; or the holder members, where they pass around the tufts, may be so flattened as to distribute the pressure which they apply. Again, the brush may be made of tufts and holders without the long handle such as is required for sweeping streets or floors, and a head or back of the proper sort may be applied.

It is within my contemplation, and within the protection of the appended claims, to make the intermediate loops or tongues *h* relatively shorter than as shown here, and to interlock the overlapping tongues of the complementary members one with another by keys or rivets, in essentially the same manner that the eyes *e* and *f* are locked together, instead of by twisting said loops around one another.

One great advantage of this invention, as compared with other is its simplicity, and the fact that the tufts can be assembled

with the holders, and the latter made perfectly secure, by manipulation, for the production of which only a sense of touch is necessary, wherefore the brush can be made 5 entirely by blind workers. Particularly, there is no need for driving nails. Another advantage is that the tufts are more securely clamped and held than they are in rigid brush heads having sockets of fixed 10 size, where nails are depended upon to pierce the tufts and crowd the material against the walls of the sockets.

What I claim and desire to secure by Letters Patent is:

15 1. A brush comprising tufts and a holder, said holder having opposite complementary members each with the complementary parts of sockets to receive the tufts and with intermediate projecting tongues, the tongues 20 of said members being interlocked with one another and the said socket, parts being forcibly held against the interposed compacted tufts and securing the latter against relative endwise movement.

25 2. A brush comprising tufts of brush material, and holders therefor consisting of complementary members formed with opposite bends each arranged and adapted to furnish the half of a tuft-receiving socket complementary to the opposite bend of the other member, and said members having between said socket-forming bends, loops which are bent up out of the plane of said bends; the loops contiguous to one another of the complementary members extending in opposite directions and being overlapped and interlocked with one another.

30 3. A brush made of tufts, and a holder comprising complementary members having eyes at their ends, a series of bends between their ends, and intermediate loops between the bends and projecting oppositely thereto, and coupling means connecting the end eyes of the said complementary members together, 45 the intermediate loops being bent and hooked into one another, and said bends holding the tufts within them under compression.

40 4. A brush comprising tufts and binding means for said tufts consisting of two wires 50 having eyes at their ends and bent zigzag between their ends, the outward bends of such wires forming the halves of sockets to receive the tufts, the wires being arranged opposite and complementary to each other 55 embracing the tufts, the intermediate or inward bends thereof forming tongues which are overlapped and bent about one another and hooked together.

50 5. A brush comprising tufts and binding 60 means for said tufts consisting of two wires

having eyes at their ends and bent zigzag between their ends, the outward bends of such wires forming the halves of sockets to receive the tufts, the wires being arranged opposite and complementary to each other 65 embracing and applying pressure forcibly against opposite sides of the tufts, the intermediate or inward bends thereof forming tongues which are overlapped and bent and hooked together, and coupling means passing through the end eyes of the complementary wires.

6. A brush comprising a handle, a series of tufts and means for binding said tufts and connecting them to the handle, said 75 means comprising complementary members each having bends to form the complementary parts of sockets and having projecting tongues between said sockets, said members being arranged to embrace and press upon 80 opposite sides of the tufts and of the handle respectively, and said tongues being overlapped and interlocked, the complementary members then being held to exert forcible pressure against the tufts and the handle 85 whereby to prevent relative endwise movement of either.

7. The method of making a brush which consists in providing a holder member having open sockets for the receipt of brush 90 tufts and oppositely-projecting open loops, placing brush tufts in said open sockets, placing a similar and complementary holder member upon the opposite sides of the tufts, and causing the open loop portions of the respective members to overlie one another, 95 and then passing a tool through the openings defined by said overlapping loops and turning the tool so as to bend said loops about one another and to draw the complementary parts of the sockets toward one another against the tufts.

100 8. The method of making a brush which consists in providing two substantially similar complementary holder members each having open sockets for the reception of brush tufts and oppositely projecting tongues between said sockets, placing brush tufts in the open sockets of one of the members, placing the complementary member against 105 the tufts, causing the tongues of the members to overlap, and then forcibly crowding the members against the opposite sides of the tufts and securing the overlapping tongues together, thereby binding the tufts 110 frictionally in the sockets.

In testimony whereof I have affixed my signature.

PETER KRUMSCHEID.
